UNITED STATES PATENT OFFICE.

AUGUSTINE DAVIS, OF CHICAGO, ILLINOIS, AND JAMES H. BIRCH, OF ELKHART, INDIANA.

GAS-GENERATOR.

No. 868,847.

Specification of Letters Patent.

Patented Oct. 22, 1907.

Application filed June 3, 1905. Serial No. 263,617.

To all whom it may concern:

Be it known that we, AUGUSTINE DAVIS and JAMES H. BIRCH, citizens of the United States, residing at Chicago, in the county of Cook and State of Illinois, and at 5 Elkhart, in the county of Elkhart and State of Indiana, respectively, have invented certain new and useful Improvements in Gas-Generators, of which the following is a specification.

This invention relates to acetylene gas generators of 10 that type wherein the carbid of calcium is fed to the water; and it consists in certain improvements upon an acetylene gas generator forming the subject matter of Letters Patent No. 719,091, granted to Augustine Davis on the 27th day of January, 1903.

15 Our present improvements relate to those parts of the generator disclosed in the aforesaid patent which effect and control the discharge of water from the generation chamber and the venting of the generation chamber during the filling and emptying of the latter.

20 In the machine of the aforesaid patent the overflow of the water from the generating chamber and the venting of the latter during the filling and emptying operations are performed through the agency of separate conduits, the overflow passage being guarded by a water 25 seal in a drainage chamber.

The principal object had in view in the development of the present invention has been to render possible the use of an overflow drainage chamber on small sizes of machines, which has heretofore proved impossible on 30 account of the limited vertical dimensions of the generation chamber and the fact that insurance regulations prescribe a water seal of at least 12 inches against gas pressure in the generation chamber. This object we have accomplished by dispensing with the water seal 35 overflow conduit heretofore used, and employing in lieu thereof a single valved pipe connecting the interior of the generation chamber at the maximum water level with the drainage chamber, which pipe combines the functions of an overflow pipe from the generation to the 40 drainage chamber and a vent pipe serving to discharge and admit air during the filling and emptying of the generation chamber, respectively.

A minor object of the invention has been to simplify the construction of the machine in respect to the above- 45 mentioned features by a reduction in the number of necessary parts.

Our present improvements are illustrated in the accompanying drawings, in which is shown simply so much of the machine disclosed in the Patent, No. 50 719,091, as is necessary to a clear understanding of the present invention; and referring thereto,—

Figure 1 is a side elevational view, partly broken out to disclose the interior mechanism, of the machine, omitting the superposed carbid-feed motor; Fig. 2 is a 55 central vertical section through the machine; and Fig.

3 is a horizontal section at a point slightly above the drainage chamber.

Referring to the drawings, and briefly describing the principal parts of the machine with which our present improvements are associated, 5 designates the cylindrical stationary outer tank or shell of the apparatus, the open upper end of which is entered by an annular-shaped bell 6, the upper end of which latter constitutes the gas collecting chamber. In the lower portion of the tank 5 is located the generation chamber 7, the side 60 walls of said chamber being constituted by the cylindrical walls of the outer shell or tank 5, and its upper and lower walls being constituted by conical plates or partitions 8 and 9, respectively. The generation chamber 7 is in free communication with the lower end of a 70 carbid-feed chamber 10 disposed therabovc and coaxially therewith, said chamber being formed by a tube or cylinder 11 resting upon or formed integral with the upper partition 8 and extending upwardly and coaxially through the bell 6. Within the carbid-feed 75 chamber is located the carbid-feed mechanism, indicated by 12. The concave bottom plate 9 of the generation chamber has a downwardly inclined lateral outlet tube 13, the outer end of which is closed by a pivoted gate-valve 14.

80 On one side of the tank 5 is located the mechanism for supplying the water to the generation chamber, the same comprising a vertical filling tube 15 having a laterally swinging cap or cover 16, said tube surrounding an inner hood 17 which latter provides a water seal, and 85 communicating with the interior of the generation chamber through a port 18. Through a notch formed in the inner edge of the cap 16 extends a tube 19 that is connected with a superposed water supply tank (not shown), whereby the machine is supplied intermittently with water during the carbid-feed. A rod 14^a connected to the gate-valve 14 extends upwardly through guides 15^a on the filling tube 15, its upper end lying beneath the overhanging edge of the cover 16 whereby said gate-valve cannot be raised until said 95 cover 16 has been opened.

20 (Fig. 1) indicates the gas discharge pipe leading from the roof of the generation chamber into a water-sealed hood 21, whence the gas flows into the gas collecting chamber in the upper end of the bell 6, the gas passing thence by a pipe 22 into a filter chamber 23, from the lower end of which latter it is discharged through a service pipe 24 leading through the wall of the tank.

The machine as thus far described is identical with 105 that disclosed in the aforesaid patent, No. 719,091, to which reference may be had for a more complete description.

Referring now to those parts wherein our present improvements more particularly reside, 25 designates a 110

drainage chamber having a closed top and located wholly exteriorly of the generation chamber, being applied to the side wall of the tank to one side of the inlet tube 15, as shown in Fig. 3. In this chamber is a discharge pipe 26 that enters the chamber near its upper end and depends within the chamber nearly to the bottom of the latter. Communicating with this chamber through its top wall is a combined overflow and vent-pipe 27, the inner end of which extends through the wall of the tank 5 into the generation chamber, terminating at a point coincident with the maximum level of the water in said chamber, as best shown in Fig. 2, wherein the relative location of said pipe is indicated by heavy dotted lines. The opposite end of said pipe, as above stated, taps the top wall of the drainage chamber 25, and the external portion of said pipe is provided with a vent-valve 28 similar to the vent-valve described in the aforesaid patent, No. 719,091, the stem of said valve having a bent rod connection 29 to the cap or cover 16 of the filling tube, the connection being such that when said cap is opened the vent-valve is opened, and vice versa. Communicating with the upper end of the drainage chamber 25 is a blow-off pipe 30 that taps the top wall of said chamber, said blow-off pipe having a branch 31 passing through the wall of the tank and extending up into the bell in order to relieve the pressure when said bell rises to an abnormal or dangerous height. This blow-off branch and its functions are, however, old, and constitute no essential part of our present improvements. The service pipe 24 also has a sealing extension 24^a depending into the drainage chamber 25, which latter is also an old feature and unrelated to our present improvements.

Referring, now, to the operation of our improved machine, assuming that the generation chamber is empty and is to be filled with water, this is done by swinging the cover 16 outwardly, which opens the vent-valve 28, and pouring the water into the upper end of the filling tube 15. The opening of the vent-valve 28 provides a passageway for the displaced air through the pipe 27, the upper end of chamber 25 and the blow-off pipe 30. Similarly, assuming that the generation chamber is to be emptied, the cover 16 is swung to one side, preliminary to opening the gate-valve 14 which opens the vent-valve 28 and allows air to be drawn in through blow-off pipe 30, the top of the drainage chamber 25, and pipe 27, to replace the water and sludge drawn off.

From the foregoing the venting functions of the pipe 27 will be readily apparent. It is also evident that during the filling of the generation chamber with water (the vent-valve 28 being open), as soon as the water reaches the level of the open inner end of the pipe 27 it will overflow through the latter into the drainage chamber 25, filling the latter to the height at which the discharge pipe 26 taps said chamber, thereby providing a water seal in said chamber equal to the height of the internal portion of the discharge pipe. When the machine is in normal operation generating gas, the vent-valve 28 is closed, thus preventing escape and waste of gas into the drainage chamber, and taking the place of

the water seal heretofore required on the overflow pipe or conduit. The water seal required for the service and discharge pipes is very small, and hence a drainage chamber of limited vertical dimensions can be used, which is an important factor in connection with small machines where the top wall of the generation chamber is too low to permit a twelve inch seal. 65

From the foregoing it will be seen that our present invention dispenses with the necessity of a separate overflow pipe from the generation chamber into the drainage chamber, giving the function of this overflow pipe to the valved vent-pipe, thus reducing the number of parts and simplifying the machine. 70

The exact form and relative disposition of the parts as herein shown and described are not essential, so long as the feature of combining the overflow and venting functions in a single pipe is preserved. 75

We claim:

1. In an acetylene gas generator, the combination with a generation chamber and means for supplying water thereto, of a drainage chamber, and a combined vent and overflow pipe connecting said generation and drainage chambers, the lower end of said pipe terminating above the water level in the drainage chamber, substantially as described. 80

2. In an acetylene gas generator, the combination with a generation chamber and means for supplying water thereto, of a drainage chamber located exteriorly of said generation chamber, and a combined vent and overflow pipe connecting the upper portions of said generation and drainage chambers, the lower end of said pipe terminating above the water level in the drainage chamber, substantially as described. 85

3. In an acetylene gas generator, the combination with a generation chamber and means for supplying water thereto, of a closed drainage chamber located exteriorly of said generation chamber and provided with a water-sealed discharge pipe, a combined vent and overflow pipe connecting the upper portions of said generation and drainage chambers, and a blow-off pipe communicating with the upper portion of said drainage chamber, substantially as described. 95

4. In an acetylene gas generator, the combination with a generation chamber having a filling tube provided with a cover, of a drainage chamber located adjacent to said generation chamber, a combined vent and overflow pipe connecting said generation and drainage chambers, and a valve in said pipe having an actuating connection to the cover of said filling tube whereby when the latter is opened said valve is opened, substantially as described. 105

5. In an acetylene gas generator, the combination with a generation chamber having a water-sealed filling tube provided with a cover, of a closed drainage chamber located exteriorly of said generation chamber, a water-sealed discharge pipe in said drainage chamber, a combined vent and overflow pipe connecting the upper portions of said generation and drainage chambers, a valve in said pipe having an actuating connection to the cover of said filling tube, and a blow-off pipe tapping the upper end of said drainage chamber, substantially as described. 110
